UNITED STATES PATENT OFFICE.

JOHN S. WALKER, OF CLAREMONT, NEW HAMPSHIRE.

SAND-BAND FOR VEHICLES.

SPECIFICATION forming part of Letters Patent No. 427,137, dated May 6, 1890.

Application filed February 4, 1890. Serial No. 339,139. (No model.)

To all whom it may concern:

Be it known that I, JOHN S. WALKER, a citizen of the United States, residing at Claremont, in the county of Sullivan and State of New Hampshire, have invented certain new and useful Improvements in Sand-Guards for Vehicle-Wheels; and I do hereby declare the following to be a full, clear, and exact description of the invention, such as will enable others skilled in the art to which it appertains to make and use the same.

My invention relates to certain novel improvements in sand-guards for the wheels of vehicles; and my objects are mainly to exclude the sand, mud, &c., from the interior of the hub and the collar of the axle; also, to provide a two-part or longitudinally-divided hinged guard, which is packed at the junction of the edges by means of rubber, leather, or other suitable material.

Other features of my invention, together with those above referred to, will be fully understood from the following description and claims, taken in connection with the annexed drawings, in which—

Figure 1 is a side view, in detail, showing my improved sand-guard applied to a wheel-hub, the upper hinged guard-section being raised. Fig. 2 is a diametrical section in detail of the same parts enlarged, showing the cap-sections closed. Figs. 3 and 4 are perspective details of the two sections of my improved sand-guard.

Similar letters of reference refer to like parts in the several figures.

Referring to the annexed drawings by letters, A designates the axle-bar of a vehicle, B the axle proper, C the hub of the wheel, and a the usual collar on the axle, which parts are or may be made in the usual well-known manner.

D designates the central metal hub-band, between which the tenons of the spokes pass into the hub.

F F' designate the two hinged parts of my improved sand shield or guard. These parts are longitudinal half-sections of a cylinder. The part or section F is hinged in a suitable manner at b to the inner band C', and the

part or section F' is hinged at b' to this band. It will be seen by reference to Figs. 3 and 4

that I provide longitudinal interlapping joints c for said sections, also similar transverse joints formed by grooved edges f on the upper hinged section, adapted to receive the edges of the lower section, and into the groove of the edge of the upper section I may insert a packing of rubber, leather, or other suitable material, which, when the two sections are closed, as shown in Fig. 2, will make tight joints and effectually exclude sand, mud, &c., from the axle and the collar a. It will also be observed that the inner edges of the inner end of my improved sand-guard are practically closed inside of the collar a', the latter serving as a cover or flange for the aperture through the inner ends of the guard-sections when these sections are closed. I am thus able to keep what little lubricant is used free from grit, and consequently prevent in a great measure gumming of the axle about the hub.

For the purpose of affording ready access to the axle, and also for allowing the removal of the wheel when desired, I am able, by reason of hinging the sections F F' to the inner band C' of the hub, to separate their inner ends, so as to clear the collar a. When the said sections are together, as shown in Fig. 2, they may be secured in this position by means of a hasp, staple, lock, or other suitable fastening. My device when thus fastened, is an additional safeguard to the nut N to prevent the wheel getting off, should this nut be lost, as the guards close over the collar a on the axle, as shown and described.

Having thus described my invention, what I claim as new, and desire to secure by Letters Patent, is—

The combination, with the hub of a vehicle and the collared axle-bar, of the guard-sections F F', hinged to the hub and provided with packing-joints, and a locking device, substantially in the manner and for the purpose specified.

In testimony whereof I affix my signature in presence of two witnesses.

JOHN S. WALKER.
